[57] CLAIM

The ornamental design for a vaporizer for insecticides and rodenticides, as shown.

DESCRIPTION

FIG. 1 is a top view of a vaporizer for insecticides and rodenticides embodying my new design;

FIG. 2 is a rear view of the vaporizer for insecticides and rodenticides taken in the direction of line 2—2 of FIG. 1;

FIG. 3 is a front view of the vaporizer for insecticides and rodenticides taken in the direction of line 3—3 of FIG. 6;

FIG. 4 is a left side view of the vaporizer for insecticides and rodenticides;

FIG. 5 is a right side view of the vaporizer for insecticides and rodenticides;

FIG. 6 is a bottom view of the vaporizer for insecticides and rodenticides;

FIG. 7 is a bottom view of the vaporizer for insecticides and rodenticides when open; and

FIG. 8 is a front view of the vaporizer for insecticides and rodenticides when open taken in the direction of line 8—8 of FIG. 7.
